UNITED STATES PATENT OFFICE.

EMANUELE MOLINARI, OF GENOA, ITALY, ASSIGNOR TO SOCIETÀ IN PARTECIPAZIONE PER LA COMBUSTIONE LIQUIDA, OF GENOA, ITALY, A COMPANY.

HYDROCARBON-BURNER.

No. 885,357.

Specification of Letters Patent.

Patented April 21, 1908.

Application filed May 2, 1906. Serial No. 314,825.

To all whom it may concern:

Be it known that I, EMANUELE MOLINARI, subject of the King of Italy, residing at Genoa, Italy, have invented new and useful 5 Hydrocarbon-Burners, of which the following is a specification.

My invention relates to apparatus for burning hydrocarbons and their derivatives and especially contemplates the provision of 10 an apparatus wherein the heat given off by the burning oil vaporizes the liquid hydrocarbon as it passes from the cistern to the burner.

The detail construction will appear in the 15 course of the following description in which reference is had to the accompanying drawing, forming a part of this specification, like numerals designating like parts throughout the several views, wherein

20 Figure 1 is a side elevation of a hydrocarbon burner constructed in accordance with my invention, and Fig. 2 is a plan view thereof.

In the practical embodiment of my invention, I employ a metallic casing, formed with 25 the floor-section H and the integral upper casting G, surmounted by a tank or cistern A from which the liquid hydrocarbon or hydrocarbon derivative to be consumed flows through a plurality of feed pipes M to an inclined surface B upon said casting G, which surface is at first precipitous and steep, but after a short descent bends so as to form a long inclined platform I down which the liquid fuel slowly flows. This inclined surface 30 D is pierced to form a plurality of ports or openings d and long parallel slots E alined and spaced from each other a distance corresponding to that between the feed-pipes M are cut in the inclined platform I, and

40 through a port or opening C in the casting G connection is made with a powerful blower or like air-current supply so that an air-current passes through C into the interior F of the burner from which it issues through the 45 spaced openings d in the part B and the parallel slots E in the angular platform.

The operation is as follows: The liquid hydrocarbon or hydrocarbon derivative flows from the cistern A through feed pipes M to the inclined surface B, which surface being heated 50 by the flame of the burner partly vaporizes the descending oil. The portion of the oil not vaporized continues to flow down the angular platform until struck by the current of air issuing through the ports d and the parallel 55 slots E, which nebulizes the same and blows it into the flame of the burner where it is consumed together with the hydrocarbon vapor from the part B. The flame may come in contact with a row of firebricks L at the top 60 of the burner, the incandescence of which would greatly assist in vaporizing the oil.

It is evident, the surface of the burner must be first heated by burning the nebulized oil before the vaporization will take place and 65 that the higher the temperature of said surface and the fire brick the more complete will be the vaporization.

Having described my invention, I claim:

In a hydrocarbon burner, the combination 70 with a cistern adapted to contain liquid fuel, of a metallic casing provided with a port for the admission of air therein, said casing having its upper surface formed with a relatively steep inclined portion and a relatively slight 75 inclined portion, said casing being further provided with a plurality of air-discharge alined openings at the juncture of the relatively steep and slight inclined portions and with a plurality of spaced air-discharge slots 80 extending therethrough longitudinally of said relatively slight inclined portion and at substantially right angles to said air-discharge openings.

In testimony whereof I have affixed my 85 signature in presence of two witnesses.

EMANUELE MOLINARI.
